FREEMAN F. MYRICK, OF DUBLIN, NEW HAMPSHIRE.

Letters Patent No. 73,825, dated January 28, 1868.

IMPROVED THREAD AND YARN-HOLDER.

The Schedule referred to in these Letters Patent and making part of the same.

TO ALL WHOM IT MAY CONCERN:

Be it known that I, FREEMAN F. MYRICK, of Dublin, in the county of Cheshire, and State of New Hampshire, have invented a new and improved Thread and Yarn-Holder; and I do hereby declare that the following is a full, clear, and exact description thereof, which will enable others skilled in the art to make and use the same, reference being had to the accompanying drawings, forming part of this specification.

This invention relates to a new and improved device for holding balls or spools of yarn or thread, while knitting, crocheting, or performing similar work.

The invention consists in having a spindle, which passes through the ball or spool, fitted in a frame constructed of a metallic bar, bent or made of such a form that the spindle may be fitted between its ends, and retained between them, by the spring or elastic pressure of the bar or frame.

The object of the invention is to obtain a simple and economical device for the purpose specified, and one which will admit of having the ball or spool adjusted to it with the greatest facility.

The drawing represents a side view of my invention.

A represents a metallic bar of semicircular shape, and having its ends bent over in loop-form, as shown at *a a*, the ends of said bar which form the inner sides of the loops having holes drilled through them, one through each end, directly opposite the outer part of the loops. This bar A constitutes the frame of the device, to receive and hold a spindle, B, which is simply a metal rod, having its ends of such a size that they may be fitted in the holes at the ends of the frame, the outer parts of the loops *a a* preventing the spindle being displaced by a longitudinal movement of the same, as will be fully understood by the drawing. The spindle is fitted in the frame by springing apart the ends of the frame, the elastic pressure of the latter retaining the spindle in place, and, therefore, in order to remove the spindle, all that is necessary is to spring apart the ends of the frame. The frame, at about its centre, is provided with an eye, b, either a swivel or a fixed one, through which a tape or chain passes, by which the device may be suspended on the arm of the person using it, or to any convenient fixture. The spindle B is passed through the ball or spool, the latter turning on the spindle, or the spindle turning in the frame. In the drawing, a ball of yarn is shown on the spindle.

Having thus described my invention, what I claim as new, and desire to secure by Letters Patent, is—

The combination of the frame A with the spindle B, substantially in the manner as and for the purpose set forth.

The above specification of my invention signed by me, this 9th day of December, 1867.

FREEMAN F. MYRICK.
